WALTER G. PETTIBONE, OF WILMINGTON, CALIFORNIA

PROCESS AND MEANS FOR FILTERING AND COOLING THE SMOKE OF TOBACCO PIPES

Application filed January 9, 1929. Serial No. 331,367.

This invention relates to smoking pipes, and has for one of its objects to provide an article of this character which shall be adapted to deliver a cool, satisfying smoke that will not burn the tongue.

To attain this and other objects, the invention comprehends the provision of a pipe having a filtering and cooling means which shall consist of tobacco in a shredded or other finely divided state and through which the smoke will pass on its way from the bowl to the mouthpiece of the pipe.

The invention also comprehends the provision of a pipe embodying means arranged within its stem and adapted to hold a tube containing the filtering and cooling medium and so support the tube as to protect the medium from any saliva entering the stem.

This invention also comprehends the provision of a pipe wherein the holding means shall be adapted to be so arranged within the stem as to permit the filtering and cooling medium to be placed directly in the stem and prevent the communication between the bowl and stem from becoming clogged by the medium.

The invention consists in the construction, combination and arrangement of parts hereinafter fully described and claimed, and illustrated in the accompanying drawings, wherein:

Figure 1 is a view partly in elevation and partly in vertical section of a smoking pipe constructed in accordance with my invention;

Figure 2 is a view in side elevation of the several parts of the pipe arranged in separated relation, and

Figure 3 is a view partly in elevation and partly in vertical section illustrating that application of the holding means which permits the filtering and cooling medium to be placed directly in the stem of the pipe.

Referring in detail to the drawings, 1 designates the bowl, 2 the stem and 3 the mouth-

piece of the pipe. The bowl 1 is provided with a boss 4 which is preferably formed integrally therewith and is provided with a passage 5 communicating with the bowl. A coupling 6 is arranged on the boss 4, and is screw-threadedly engaged therewith as shown in 7. The coupling 6 has its front edge flanged inwardly into engagement with the screw threads of the boss 4, as shown at 8, so as to prevent it from having any accidental turning movement on the boss. The stem 2 which may be straight, as shown in the drawings, or curved longitudinally, is provided with laterally enlarged and internally screw threaded ends 9 and 10. The front end 9 of the stem 2 is arranged on the coupling 6 and engages the external screw threads 11 on the coupling. The end 10 of the stem 2 receives the externally screw threaded front end 12 of the mouthpiece 3. While I have shown the stem provided with enlarged ends through the medium of which it is connected to the bowl and the mouthpiece, I wish it understood that such ends may be omitted and the stem connected to the other parts in any well known or appropriate manner.

The coupling 6 has its rear end closed, and is provided at said end thereof with a hollow boss 13 which is arranged within and spaced from the stem 2 and which is provided with an opening 14 registering with the passage 5. The boss 13 is internally screw threaded, as shown at 15, and it is provided with a conical outer surface which tapers in the direction of its rear end. A holder 17 of substantially conical formation is arranged within the stem 2, and is provided with a reduced and externally screw threaded stem 18 which is detachably engaged within the boss 13 and is provided with a passage 19 registering with the opening 14. A filtering and cooling cartridge 20 is supported within the stem 2 by the holder 17. The filtering and cooling cartridge 20 is smaller diametrically

- than the stem 2, has its front end removably arranged in the holder 17 and extends from the holder to a point in close proximity to the front end of the mouthpiece 3. The filtering and cooling cartridge 20 comprises a casing 21 fully open at both ends and by preference made from paper, and a filtering and cooling medium 21 preferably consisting of tobacco in a shredded or other finely divided state.
- 10 If desired the filtering and cooling medium 21 may be placed directly in the stem 2, as shown in Figure 3. When this is to be done, the holder 17 is reversed and arranged on the boss 13 with the boss snugly fitting therein.
- 15 The holder 17 will, when in this position, prevent the closing of the passages between the bowl 1 and stem 2 by the filtering and cooling medium.

When the pipe is in use, the smoke passes 20 directly from the bowl 1 into the filtering medium 21, and after passing through the filtering and cooling medium it will enter the mouthpiece 3. It will thus be understood that the smoke will be freed of many of its impurities and its temperature materially lowered, with the result that the pipe will deliver a cool satisfying smoke that will not burn the tongue. As the cartridge 20 is supported by the holder 17 out of contact with 25 the stem 2, the filtering and cooling medium 21 will be protected from any saliva entering the tube 2. As the cartridge 20 is removably engaged with the holder 17, and as the stem 2 is detachably secured to the bowl 1, 30 the cartridge may be removed and a new one substituted therefor easily and quickly. The filtering and cooling medium 21 when placed directly in the stem 2 may also be readily removed and new material substituted therefor.

35 As the bowl 1, stem 2, mouthpiece 3 and holder 17 are detachably connected together they may be separated in order to permit them to be conveniently cleaned.

40 While I have described the principle of the invention, together with what I now consider to be the best embodiments thereof, I desire to have it understood that the embodiments shown are merely illustrative, and that such changes may be made as are within the scope 45 of the invention and claimed.

What I claim is:

1. In a combination of the class described, a bowl, a stem, a mouthpiece, a coupling connected to said bowl, said coupling having a 50 hollow boss which is internally screw threaded and has a conical outer surface, a conical holder having a reduced screw threaded stem, said last mentioned stem being adapted to 55 screw into said boss, at which time the conical holder will extend toward said mouthpiece, or said holder being adapted to fit upon the conical surface of said boss, at which time the screw threaded stem will extend toward 60 said mouthpiece, as and for the purposes set forth.

2. In a combination of the character described, a bowl, a stem, a mouthpiece, a supporting element at one end portion of said stem, a comparatively short and widely flared holder supported by said element, and an 70 elongated tobacco cartridge extending into said holder and protruding through said stem toward said mouthpiece, as and for the purposes set forth.

75 In testimony whereof I affix my signature.

WALTER G. PETTIBONE.
